UNITED STATES PATENT OFFICE.

CHRISTIAN H. WIEBOLD, OF LEIGH, NEBRASKA.

DOOR HANGER.

Application filed August 18, 1928. Serial No. 300,507.

This invention relates to doors of the bodily shiftable type, more particularly to doors for use in connection with barns, but it is to be understood that a door in accordance with this invention may be employed in any connection for which it is found applicable, and the invention has for its object to provide, in a manner as hereinafter set forth a novel form of door which may be readily and easily swung to a position exteriorly of the door opening and shifted and supported laterally of such opening to permit access to be had to the structure with which the door is associated.

15 A further object of the invention is to provide, in a manner as hereinafter set forth, a bodily shiftable door having connected therewith means adapted when operated to readily and easily swing the door to a position exteriorly of the door opening, and further provide whereby the door can be shifted in a lateral direction and supported adjacent the opening to permit access being had to the structure with which the door is associated.

20 25 Further objects of the invention are to provide, in a manner as hereinafter set forth, a door for the purpose referred to which is simple in its construction and arrangement, strong, durable, compact, thoroughly efficient in its use, conveniently operated, readily installed and comparatively inexpensive to manufacture.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a front elevation of a door in accordance with this invention and illustrating the door supported when positioned to one side of a door opening.

50 Figure 2 is a fragmentary view in section looking towards one side edge of the door and further illustrating the latter in supported position.

55 Figure 3 is a fragmentary view in sectional elevation illustrating the trolley for the door and a track for the trolley.

Figure 4 is a fragmentary view in sectional plan of the trolley for the door.

Figure 5 is a section on line 5—5 Figure 3.

Figure 6 is a cross sectional view of the 60 trolley track.

Figure 7 is an inverted plan of the trolley track.

Referring to the drawings in detail 1 denotes the wall of a barn, building or car 65 formed with a door opening 2 having the sides and top walls thereof rabbed as at 3 to provide a seat for a door 4 employed for closing the opening 2. Adjacent each side wall of the opening 2, there is secured to the 70 outer face of the wall 1 latch members arranged in pairs and with the members of each pair superposed with respect to each other. The latching members of one pair are indicated at 5 and those of the other pair 75 at 6 and each latching member is mounted upon a pivot 7 and the member is of a length to project over the rabbet 3 when the member is shifted to latching position. The latching members are adapted to overlap the door 80 4, that is the outer face thereof, when the door is mounted in the opening 2 thereby detachably securing the door in position to close the opening 2.

Arranged against the outer face of the 85 wall 1, a substantial distance above the top of the opening 2 and extended a substantial distance to one side of said opening 2 is a trolley track 8 consisting of a tubular member 9 having its bottom provided with a 90 lengthwise disposed slot 10 corresponding in length to the length of the member 9. Mounted in each end of the member 9 is a closure plug 11 secured to the vertically disposed leg 12 of a combined supporting and coupling 95 bracket 13. The other leg of the bracket 13 is indicated at 14 and is adapted to be positioned against the wall 1. The leg 14 has an opening 15 for the passage of a holdfast device 16 to fixedly secure the bracket 13 to the 100 wall 1. The holdfast devices for securing the plug to the leg 12 are indicated at 17.

Positioned within the track 8 and of less length than the length of the latter, as well as capable of being shifted in either direction within the track 8, is a trolley referred to generally at 18 and consisting of a frame formed of a pair of parallel bars 19, 20 standing on edge and with each bar formed with an intermediate part 21 of less width than the 110 outer part thereof. The inner face of each outer part of the frame bar, centrally of such

inner face, is formed with a boss 22. The bosses 22 formed on the inner face of the bar 19 align with the bosses 22 formed on the inner face of the bar 20. One end of the bar 19 is secured to one end of the bar 20 by a cylindrical holdfast device 23 which provides a shaft for a roller 24 of a diameter greater than the width of the outer parts of said bars. The other end of the bar 19 is secured to the other end of the bar 20 by a holdfast device 25 in the form of a cylindrical bar and which constitutes a shaft for a roller 26 and with the diameter of the latter greater than the width of the outer parts of the bars. The bars 19 and 20 are also secured together by holdfast devices 27 positioned inwardly with respect to the bosses 22, as well as being spaced therefrom and such holdfast devices 27 constitute shafts for rollers 28 which are of greater diameter than the width of the outer portions of the bars 19, 20. Between roller 24 and a roller 28 the bars 19, 20 are secured together by a holdfast device 29 which constitutes a shaft for a grooved pulley 30 positioned between the pair of bosses 22 and of less diameter than the diameter of the rollers 24, 28. The bars 19 and 20 are furthermore secured together between roller 26 and a roller 28 by a holdfast device 31 which constitutes a shaft for a grooved pulley 32, the latter being of less diameter than the rollers 26, 28. The rollers 24, 26 and 28 extend above and below the bars 19, 20 and are of a thickness to straddle the slot 10. Preferably the diameter of said rollers is substantially the same as the inner diameter of the member 9.

As illustrated, the door 4 is constructed of a series of abutting planks 33, secured together by transversely extending cross members 34, 35 arranged respectively at the top and bottom of the inner face of the door. The cross members, when the door is in position to close the opening 2, seat in the mortises indicated at 36 Figure 1.

Each end plank 33 of the door body 4 at the upper end thereof is formed with a transversely extending furcation 37 opening at the top edge of the plank. See Figure 2. Connected to the upper end of each outer plank 33 of the door body 4 and extending across the furcation 37 is an anchoring device 38 for one end of a flexible, combined hanger and vertically adjusting member 39 for the door body 4. That end of the member 39 connected with an anchoring device 38 is indicated at 40. The members 39 extend into the furcations 37. The anchoring devices 38 extend through the connecting member 34 and also through the outer planks of the door body. One member 39 extends around the pulley 30 and the other member 39 extends around the pulley 32. Preferably the vertically adjusting members are formed from a single length of cable and the cable is ar-

ranged in a manner to provide the oppositely extending members 39. As illustrated the cable is anchored, as at 41, to a drum 42 mounted on a shaft 43 which is carried by and projects outwardly from the door 4. The outer end of the drum 42 is provided with a handle 44 for the purpose of revolving the drum about the shaft 43 to wind thereon or unwind therefrom the members 39. Connected to the drum 42 is a ratchet wheel 45 which coacts with a pivoted dog 46 to arrest the shifting of the drum 42 in a direction to prevent the members 39 from winding thereof. It is to be understood that the members 39 can be formed of independent cables and have their outer ends or their lower ends fixedly secured to the drum 42. The members 39 extend at opposite inclinations with respect to each other around the pulleys 30, 32 and then depend and are anchored to the top of the door 4 at each upper corner thereof.

The track 8 is arranged in spaced relation with respect to the front of the wall 1 and a bracing means therefor is indicated at 47. Spaced supports 48 are secured to the front wall 1 adjacent the opening 2 for the door 4 when the latter is shifted to the position shown in Figure 1. The supports 48 are arranged below the bottom of the opening 2.

For opening the door, the latches 5, 6 are released, and the members 39 are wound on the drum 42 and the door will be shifted to a position so that it can be rolled open. After the door 4 has been moved to the position shown in Figure 1 the weight thereof on the trolley and track is overcome by unwinding the cable sufficiently to let the door rest on the supports 48. To close the door, the pulling members are wound on the drum 42 to the extent to bring the weight of the door on the trolley, after which the door is moved to oppose the opening 2, and then pushed therein, after which the members 39 are released enough so that the door can be moved into its seat. The latches are then moved to overlap the door to latch it in the door opening.

It is thought the many advantages of a door in accordance with this invention and for the purpose set forth can be readily understood, and although the preferred embodiment of the invention is as illustrated and described, yet it is to be understood that changes in the details of construction can be had which fall within the scope of the invention as claimed.

What I claim is:

1. In combination a track for positioning over and for extension from one side of a door opening in a lateral direction with respect to the latter, a bodily shiftable door for closing said opening, a trolley travelling on the track and including spaced, grooved pulleys, a drum carried by and projecting outwardly from the door, a flexible means winding on and off said drum, extending over

said pulleys and anchored to the top of the door for vertically shifting the latter from and to closing position with respect to the door opening and further for suspending the door, and supports for receiving the bottom of the door when the latter is shifted laterally from said side of the door opening.

2. In combination a track for positioning over and for extension from one side of a door opening in a lateral direction with respect to the latter, a bodily shiftable door for closing said opening, a trolley travelling on the track and including spaced, grooved pulleys, a drum carried by and projecting outwardly from the door, a flexible means winding on and off said drum, extending over said pulleys and anchored to the top of the door for vertically shifting the latter from and to closing position with respect to the door opening and further for suspending the door, supports for receiving the bottom of the door when the latter is shifted laterally from said side of the door opening, and said drum and door having coacting means for latching the drum from movement.

3. In combination a tubular track member having its bottom formed with a lengthwise disposed slot, means for securing said member above a door opening, said member of greater length than the width of the opening to project laterally from one side of the latter, a bodily shiftable door for closing the door opening, a trolley arranged within and travelling against the inner face of said member and provided with spaced, grooved pulleys, a rotatable drum carried by and extended outwardly from said door, flexible means winding on and off of said drum, extending through said slot and over said pulleys and anchored to the door at each upper corner thereof and providing when the drum is operated for vertically shifting the door from and to closing position with respect to said opening, said flexible means further providing a hanger for the door, and supports for receiving the bottom of the door when the latter is shifted in a lateral direction with respect to the door opening, said supports adapted to be positioned below the bottom of the door opening.

4. In combination a tubular track member

for positioning above and of greater length than the width of a door opening to project from one side of the latter, a trolley within and travelling against the inner face of said member and provided with spaced, grooved pulleys, a door for closing said opening, and windable and unwindable means connected with the door in proximity to each end of the top thereof and further in proximity to the center thereof and travelling over said pulleys for vertically shifting the door from and to closing position with respect to said opening.

5. In combination a tubular track member for positioning above and of greater length than the width of a door opening to project from one side of the latter, a trolley within and travelling against the inner face of said member and provided with spaced, grooved pulleys, a door for closing said opening, windable and unwindable means connected with the door in proximity to each end of the top thereof and further in proximity to the center thereof and travelling over said pulleys for vertically shifting the door from and to closing position with respect to said opening, and a latching device for said means.

6. In combination a tubular track member having its bottom formed with a lengthwise slot, means for supporting said member above a door opening, said member being of greater length than the width of said opening to project laterally from one side of the latter, a trolley arranged within said member and travelling against the inner face thereof and including spaced, grooved pulleys, flexible elevating and lowering means for said door, said means connected to the door at each end of its top and in proximity to its center, said elevating and lowering means extending through said slot and passing over said pulleys, for suspending the door, a winding and unwinding device for said elevating and lowering means for removing the door from closing position with respect to the door opening and for positioning the door with respect to said opening for closing the latter.

In testimony whereof, I affix my signature hereto.

CHRISTIAN H. WIEBOLD.
